UNITED STATES PATENT OFFICE.

ROBERT MACKAY, OF WALTHAMSTOW, ENGLAND.

KETTLE OR WATER-HEATER.

1,333,266.

Specification of Letters Patent.

Patented Mar. 9, 1920.

Application filed October 29, 1918. Serial No. 260,198.

To all whom it may concern:

Be it known that I, ROBERT MACKAY, a subject of the King of Great Britain, residing at 74 Shernhall street, Walthamstow, in the county of Essex, England, have invented a new and useful Kettle or Water-Heater, of which the following is a specification.

The object of the present invention is to construct an improved kettle or water heater which is adapted more particularly for use in restaurants and other places where it is advantageous to be able to draw boiling water or to obtain a supply of steam from the same outlet for heating, for instance, tea-pots.

According to the present invention the main body of the kettle has an upwardly extending water delivery pipe, which also extends into the body below the water level and is open at its lower end. At its upper end the water delivery pipe enters another tube which acts as a pouring tube and steam delivery pipe. This pouring tube, which is preferably suitably curved at its delivery end enters at its other end an upward extension of the body of the kettle where it is provided with an automatic or other steam valve. The kettle may be supplied with water through a ball valve tank, or it may be filled through an opening at its side provided with a closing valve, by which means the water level in the kettle is determined.

The apparatus is so constructed that by moving some part of it for instance forward boiling water will be delivered through the spout, whereas when said part is in its normal or upright position steam will be delivered through the said spout. In some cases the said part may be moved backward to raise steam. The movement of this said part causes relative movement between the kettle and the valves and this moving part may be the body of the kettle in which case the valves are weighted so that they do not move with the kettle or the moving part may be in the form of a lever in which case the body of the kettle does not move.

Various methods of carrying the invention into effect are illustrated in the accompanying drawings which are somewhat diagrammatic.

Figure 1 is a side elevation partly in section and Fig. 2 is a horizontal section on the line 2—2 of Fig. 1 showing a kettle

which is heated by means of a constantly burning gas ring or open fire.

Fig. 3 is a side elevation partly in section and Fig. 4 is a plan of a part thereof showing a kettle in which the gas or other heating medium is adapted to be turned on and off as the kettle is tilted backward or forward to deliver steam or boiling water.

Fig. 5 is a side elevation and Fig. 6 is a plan of part thereof showing a kettle in which the gas or other heating medium is adapted to be turned on and off by moving a lever backward or forward.

Fig. 7 is a side elevation partly in section and showing a section of a water valve and Fig. 8 is an elevation of part of a kettle showing a lever for operating a gas and a water valve simultaneously.

Fig. 9 is a plan of part of a kettle showing a steam valve in section.

Fig. 10 is a plan of part of a kettle showing electrical heating means and a switch in section.

In all the figures *a* is the lower or main body of the kettle and *a'* is the reduced upper part thereof. The main body *a* of the kettle has an upwardly extending hot water delivery pipe *b* which extends into the part *a* below the water level and is always open at its lower end. At its upper end the hot water pipe *b* enters another tube *c*, which acts as the pouring spout and steam delivery pipe. This tube *c*, which is preferably curved at its front or delivery end, enters at its rear end the upward extension *a'* of the kettle, and it is provided with a steam valve which is opened or closed by tilting the kettle backward or forward or by the movement of a lever.

In the construction shown in Figs. 1 and 2 the tube *c*, at its rear end, is formed with a valve seating *c'* and a weighted valve *c''*. The cold water inlet tube *d* is mounted in bearings *d'*, and has a branch *d''* which enters the body *a*. This branch *d''* is provided, at its rear end, with a valve seating *d''* and a hinged weighted closing valve *d''*. The tube *d*, at one end, enters a union *d''* which allows the tube *d* to rotate in its bearings *d'*. The union *d''* is connected to the water supply pipe *e*, which is connected to a ball valve tank *k* which regulates the height of water in the kettle. In the position shown in Fig. 1, the valve *d''* is open and water may enter the kettle until it is shut off by the ball valve. In the same position steam is being

delivered through the pipe c^2 is open. When the kettle is tilted forward the water inlet valve d^4 and the steam valve c^2 are both closed, and boiling water then 5 passes up the tube b and is delivered through the spout. A is a gas burner to heat the vessel a .

In the construction shown in Figs. 3 and 4, the parts b , c , c^1 , and c^2 , are like the 10 parts shown in Figs. 1 and 2 and operate in like manner. The kettle a , a^1 , in this construction is mounted on trunnions f , one of which is shown and this may be a water inlet tube connected to the ball valve tank by 15 a union as shown in Figs. 1 and 2. This union, or the inner end of the water inlet tube, may be provided with a valve D^4 which is open when the kettle is horizontal or tilted backward and which is closed when 20 the kettle is tilted forward from the horizontal position, such a valve D^4 is shown in section in Fig. 7. The perforated outer part D^4 is fixed rigidly to the body part a^1 and moves therewith over the water inlet tube f which is cut away as shown. The 25 body a of the kettle carries a cam g , the ends of which act against a spring plunger g^1 to open the gas valve g^2 when the kettle is tilted backward or forward from the central horizontal position. In the central horizontal position the depressed center part of the cam g allows the spring plunger g^1 to close the gas valve g^2 . When it is desired to 30 obtain steam only through the spout, the kettle is tilted back, thereby turning up the gas and leaving the steam and water valves open. Having obtained as much steam as desired, for instance, the heating of a teapot, the kettle is pulled through its central 35 horizontal position and is tipped forward, when the steam valve c^2 is closed, the water inlet valve P^4 is closed, but the gas valve g^2 is open. In this position boiling water is delivered through the spout. If one of the 40 trunnions f is not a water inlet tube, the upper part a^1 of the kettle is provided with a filling orifice a^2 and screw stopper a^3 . In the construction shown in Figs. 5 and 45 6, the kettle is a fixture and the valves are operated by the movement backward or forward from the central position of the lever h pivoted to the kettle at h^1 . The steam valve c^2 is mounted upon a shaft c^3 , on the end of which is fixed the crank c^4 , which is connected by the rod h^2 with the lever h . In the central and backward positions of the lever h , the valve c^2 remains open. In the forward position of the lever h , the valve c^2 will be closed against its seating c^1 . The 50 lever h is shown with a square h^3 to engage a water cock D^4 such as that shown in Fig. 7 connected to a ball valve tank. In this construction the lever h operates the outer part D^4 around the fixed water inlet tube f . 55 The parts D^4 and f are shown dotted in

Figs. 5 and 8. In the center position, and when the lever h is pushed backward, the water-cock D^4 will remain open, but when the lever h is pulled forward, the water inlet cock will be closed. At its lower end the 70 lever h carries a cam g , similar in shape to that shown in Figs. 3 and 4, and which acts upon the spring plunger g^1 of the gas valve g^2 as described with respect to that figure. If desired the lever h , pivoted at h^1 , may 75 as shown in Fig. 8 carry a second cam i having a projection i^1 at one end only and acting upon a spring plunger j forming part of a water inlet valve j^1 . This cam i will be arranged to leave the plunger in its outer 80 position and the water inlet open when the lever h is central or pushed backward. The cam i will, however, push the spring plunger j inward and close the water inlet valve j^1 when the lever h is pulled forward. 85

It will be understood that steam or electricity may be used instead of gas as the heating medium, and that what is described as the gas valve g^2 may be a steam valve or electric switch operated by the cam g and turned off when the lever h is in its middle position and turned on when the lever h is in a forward or backward position. Such a steam valve h is shown in Fig. 9 in which k^1 is a spring pressed plunger having a 90 perforation at k^2 . The valve h is bored through at k^3 . As shown in the drawing the valve h is closed but when the cam g is moved forward or backward it depresses the plunger k^1 and the perforation k^2 comes 95 in alignment with the passage k^3 and allows steam to flow therethrough and to the steam pipes h^4 shown in Fig. 9.

Fig. 10 shows an electric switch operated by the cam g . The switch comprises a 105 spring pressed plunger l which enters the switch body l^1 . Through this body and insulated therefrom are two contact blades l^2 . The plunger l has an insulation block l^3 at its lower end and when the plunger l 110 is depressed by the cam g moving forward or backward, it causes the blades l^2 to make contact with each other and allows current to pass to the electric heaters indicated diagrammatically at l^4 in Fig. 10, 115 which heaters are located below the water in the kettle. When the lever h is pulled forward, the steam and water valves being closed and the heating medium being in operation, steam pressure will accumulate and 120 deliver water through the pipe b and spout. When the lever h is pushed backward steam only will be delivered.

What I claim as my invention is:

1. In an improved water heater the combination of a water vessel, a water delivery pipe open at its lower end beneath the water level, a pouring tube and steam delivery pipe into which the water delivery pipe enters at its upper end, a valve on the 125 130

pouring tube and steam delivery pipe and means for closing said valve when water is being delivered substantially as set forth.

2. In an improved water heater the combination of a water vessel, a water delivery pipe open at its lower end beneath the water level, a pouring tube and steam delivery pipe into which the water delivery pipe enters at its upper end, a valve on the pouring tube and steam delivery pipe, means for closing said valve when water is being delivered, a water inlet pipe, a valve on the water delivery pipe and means for closing this latter valve simultaneously with the valve on the pouring spout and steam delivery pipe substantially as set forth.

3. In an improved water heater the combination of a water vessel, a water delivery pipe open at its lower end beneath the water level, a pouring tube and steam delivery pipe into which the water delivery pipe enters at its upper end, a valve on the pouring tube and steam delivery pipe, a water inlet pipe, a valve on this latter, a pivoted part and means operated by the pivoted part for simultaneously closing and opening the two said valves substantially as set forth.

30 4. In an improved water heater the combination of a water vessel, a water delivery pipe open at its lower end beneath the water level, a pouring tube and steam delivery pipe into which the water delivery pipe enters at its upper end, a valve on the pouring tube and steam delivery pipe a water inlet pipe, a valve on this latter, a pivoted part, means operated by the pivoted part for simultaneously closing and opening the two said valves, means for heating the vessel and means for putting into action the heating medium when the other two valves are closed substantially as set forth.

45 5. In an improved water heater the combination of a water vessel, a water delivery

pipe open at its lower end beneath the water level a pouring tube and steam delivery pipe into which the water tube enters, a valve on the pouring tube and steam delivery pipe, a water inlet pipe, a valve on this latter, a gas valve, a pivoted part and means operated by said pivoted part for simultaneously closing the valve on the steam delivery pipe and the valve on the water inlet pipe and for opening the gas valve substantially as set forth. 50

6. In an improved water heater the combination of a water vessel, a water delivery pipe open at its lower end beneath the water level, a pouring tube and steam delivery pipe into which the water tube enters, a valve on the pouring tube and steam delivery pipe, a water inlet pipe, a valve on this latter, a pivoted lever, a heat regulating device and means operated by said lever for simultaneously closing the valve on the steam delivery 60 pipe and the valve on the water inlet pipe and for operating the heat regulating device to increase the heat substantially as set forth. 65

7. In an improved water heater the combination of a water vessel, a water delivery pipe open at its lower end beneath the water level a pouring tube and steam delivery pipe into which the water tube enters, a valve on the pouring tube and steam delivery pipe, a water inlet pipe, a valve on this latter, a pivoted lever, a heat regulating device and means operated when said lever is moved in one direction for simultaneously closing the valves on the steam delivery and water inlet pipes and for operating the heat regulating 70 device to increase the heat and means operated when said lever is moved in the other direction to leave the valves on the steam delivery and water inlet pipes open and to operate the heat regulating device to increase 75 the heat substantially as set forth. 80

In witness whereof I have hereunto set my hand.

ROBERT MACKAY.
